UNITED STATES PATENT OFFICE

HAROLD N. BEEBE, OF PITTSFIELD, MASSACHUSETTS, ASSIGNOR TO GENERAL ELECTRIC COMPANY, A CORPORATION OF NEW YORK

ELECTRIC SWITCH

Application filed June 12, 1929. Serial No. 370,206.

My invention relates to improvements in electric switches and more particularly disconnecting switches for use where space is limited and safety for men and apparatus is 5 paramount.

In low voltage alternating current distribution systems, the transformer stations at the ends of the feeder cables are located in vaults, the size of which is restricted by economic factors and underground congestion. 10 Moreover, it is often necessary, particularly in congested districts to use existing vaults which were not built to meet the demands of system changes and better service. Inasmuch as the feeder circuits are operated at 15 relatively high voltages, ranging from 4,000 to 26,000 volts, the necessary insulation in view of the space limitations is of great importance especially for switches. If an insulating fluid such as oil is used for the 20 switches, it must not be allowed to escape and thereby affect the insulation and create a fire hazard. Because of the probability of dampness and even flooded conditions of the vaults, 25 water must be kept from the switch parts and the insulating fluid. Moreover, in order to insure safety and convenience for testing, 30 operation and maintenance, the switch apparatus must be safely accessible and arranged to prevent improper or dangerous operation.

It is then an object of my invention to provide an improved and simple switch which is compact and yet conveniently accessible and 35 which is fluid tight. Another object is to provide an improved switch which is suitably insulated for the desired voltages. A further object is to provide an improved switch which insures a high degree of safety 40 for both apparatus and operator under normal operating conditions and particularly during testing and maintenance.

My invention will be better understood from the following description when considered in connection with the accompanying drawings and its scope will be pointed out in the appended claims.

In the accompanying drawings, Fig. 1 is a front elevation of a double-throw switch 50 embodying my invention, the switch being

shown in one of its circuit closing positions; Fig. 2 is a part sectional elevation on the line 2-2 of Fig. 1 with the switch in the same position as in Fig. 1; Fig. 3 is similar to Fig. 2 except that the switch is shown in the circuit opening position; Fig. 4 is similar to Fig. 2 except that the switch is shown in its other circuit closing position; Figs. 5, 6 and 7 are perspective views of a part of the operating mechanism of the switch shown in Fig. 1 with the parts positioned to correspond with the conditions in Figs. 2, 3 and 4 respectively; Fig. 8 is a transverse sectional elevation of the operating mechanism with the parts positioned as shown in Fig. 6; Fig. 9 is a perspective view of the switch shown in Fig. 1 with parts omitted for the sake of clearness; and Fig. 10 is a circuit diagram illustrating an application of the switch shown in Fig. 1.

The embodiment of my invention chosen for the purpose of illustration is a three-phase double-throw switch including two relatively stationary spaced contact means such as front and back contacts 11 and 12 respectively and a cooperating movable contact means such as the contacts 13. The contacts 11 have terminals 14 and are mounted in insulators 15 supported on a member 16. As shown this member, which may be of insulating material, extends between the end plates 17. The contacts 12 may be similarly mounted but in order to use the switch for grounding purposes they are shown as mounted on a cross member 18 of electric current conducting material. This member is arranged to be grounded through a flexible lead 19 and screw connection 20 to the switch chamber or housing 21 which is cut away for clearness in showing the switch parts.

Inasmuch as the usual insulating materials are not well adapted to withstand torsional stresses and to obtain the necessary strength would mean undesirable bulk, I provide in accordance with my invention an arrangement for actuating the movable contacts 13 whereby to insure both strength and insulation without bulk. As shown this arrangement includes a contact supporting member 22 which is of insulating material

and which is mounted for movement in an arcuate path. For this purpose it may be pivotally secured to an operating member such as a shaft 23 at the ends of a crank or 5 cranks 24 secured thereto. The shaft 23 is journalled on the end plates 17 and may be of any suitable metallic material for torsion stresses and, if desired, may be provided with a coating or layer 25 of insulating material for further safety.

In order to lock the switch in its different circuit controlling positions, the extension of the shaft 23 through one of the end plates 17 may be provided with interlocking means shown as of the bar and sector type, the bar 26 being arranged to be actuated by suitable electromagnetic means 27 and to engage slots in the sector 28 which is secured to the shaft.

20 In order to control the angular position of the movable contact support 22 as the shaft 23 is rotated and the contacts 13 are moved from a position adjacent one set of stationary contacts to a position adjacent the other set so 25 as to insure proper register with these contacts, I provide in accordance with my invention relatively movable guiding elements such as an arm or arms 29 extending from the member 22 and engaging guides 30 on the end plates 17, the engagement with the guides being such as to permit the desired angular movement of the arms. For this purpose the guides may have suitably shaped and enlarged openings or a swivel mounting may 30 be used. The movable contacts 13 are connected through flexible leads 31 to entrance bushings 32 mounted in the switch casing. In order to avoid any possibility of the leads fouling each other or the switch frame, there 35 may be mounted between these leads and the end plates 17, insulating barriers 33 on cross supports 34 secured to the end plates and also insulated. These cross supports 34 may 40 also serve as adjustable members to tie the end plates together at the bottom, as shown.

In order to mount the switch relatively to its casing for easy withdrawal and replacement, the casing and walls 21, as shown in Fig. 1, may be provided with angle shelves 35. 50 In these are mounted set screws 36 which engage the end plates 17 or projections thereon so as to determine the position of the switch in its casing. Suitable fastening means such as bolts 37 extend through the shelves 35 into the end plates 17. Obviously, on withdrawal of these bolts, the end plates are movable relatively to the casing 21 and with the switch in the open position shown in Fig. 3 and upon release of the electrical connections including the ground connection 19, 20; the connections to the terminals 14, the connections of the flexible leads 31 to the bushings 32, and the auxiliary circuit conductors 38 of the electromagnetic locking means 27, 65 the switch can be withdrawn from its casing.

If the adjustment of the set screws 36 is not disturbed, replacement is readily possible or adjustment can easily be made if necessary to line up the switch relatively to its casing.

Further, in accordance with my invention, 70 I provide a switch operating means 40 whereby the switch may be locked in any of its circuit controlling positions and whereby movement from one circuit closing position through the open position to the other closed position cannot be made without some forethought on the part of the operator. The operating means 40 also includes means for maintaining a substantially fluid tight seal about the part of the operating mechanism which projects through the casing 21. As shown, the operating means includes a base 41 which is secured to the casing 21 by suitable means such as bolts 42, suitable packing 43 being interposed as shown in Fig. 8. 80 Mounted on the frame 41 is a rotatable operating member 44 which is movable to a plurality of positions, as indicated in Figs. 5, 6 and 7, and which includes a shaft portion 45 slotted at 46 to engage the flattened end 47 90 of the shaft 23, see Fig. 9.

For securing the operating member 44 in any one of its positions, I provide a locking member 48 which is pivoted on the base 41 and is provided with a locking lug 49. In 95 the open position of the switch, the locking lug 49 is arranged to be entered into a slot 50 in the operating member 44 and in either of the closed positions of the switch the locking lug 49 can be placed in the path of movement of one or the other of the lugs 51 on the operating member 44. Locking eyes 52 on the base 41 and the locking member 48 come into register when the locking member is in locking position and a padlock 53 may 100 be inserted to prevent unauthorized operation of the switch.

While the shaft portion of the operating member 44 passes through suitable packing and a gland bushing 54, this must not be so 110 tight as to prevent or make difficult the rotation of the shaft 23 and yet the switch casing must be maintained fluid tight from both within and without. I further provide in accordance with my invention for obtaining 115 this fluid tight seal an arrangement which can be released to permit rotation of the operating member 44 when desired and yet maintain an effective seal at all other times. For this purpose I provide an additional 120 packing means such as a gasket 55 where the shaft portion 45 extends through the base 41 arranged so that the locking member 48 may be operated to perform not only its locking function but also the necessary sealing function as this insures simplicity of the apparatus. For this purpose the locking member is provided with an eccentric or cam portion 56 which engages the outer extremity 125 of the shaft portion 45. With the locking 130

member in the position shown in Figs. 5 to 8 inclusive, the cam exerts considerable pressure on the shaft portion 45 thereby compressing the packing 55 around the shaft. Upon counter-clockwise rotation of the locking member as seen in Fig. 8, the pressure on the shaft portion 45 is released so that the operating member 44 is thereby more freely movable. With the release in the pressure 10 the locking feature is also unlocked so that rotation of the operating member can be effected.

In order to prevent thoughtless operation of the switch, assuming the padlock 53 has been removed, I provide means for limiting the movement of the operating member 44 from one of the circuit closing positions as shown in Fig. 5 to the circuit open position shown in Fig. 6, whereby the operating 15 member cannot be moved to the other circuit closing position shown in Fig. 7 without returning from the circuit open position to the circuit closed position shown in Fig. 5 and performing in this position a special 20 operation. As shown, this motion limiting means includes a locking element 57 pivotally associated with the operating member 44 at 58. The locking element 57 carries at its 25 other end a projection such as a pin 59 which projects through the slot 50 in the operating member into a cooperating interlocking element such as the slot 60 in a raised portion of the base 41. This slot 60 is open at one end and closed at the other end and of such length as 30 to permit the illustrated embodiment of my invention substantially a 90° movement of the operating member as will be more clearly apparent from Fig. 7, that is from the position shown in Fig. 5 to the position 35 shown in Fig. 6. In order to permit the releasing movement of the member 57, the end pivoted to the operating member 44 includes a lost motion slot. The open end of the slot 60 is such that the pin 59 in the 40 limiting link 57 can be withdrawn from the slot 60 by movement in the slot 50 of the operating member 44 only when the operating member 44 is in the position shown in Fig. 5. This is the position corresponding to engagement 45 of the contacts 13 with the contacts 11.

In the schematic circuit arrangement shown in Fig. 10 to illustrate an application of a switch embodying my invention, a polyphase high voltage feeder 61 is connected to a low voltage network 62 through the contacts 11, 13 of a switch such as shown in Fig. 1, a step down transformer 63 and a circuit breaker 64. The electromagnetic interlocking means 27 may be connected across a 55 phase of the network as shown, so that whenever the circuit breaker 64 is closed and the network is energized, or the feeder is energized, the electromagnet 27 will be excited to lock the switch sector 28 so as to prevent 60 operation of the switch 11, 13 on a live circuit. 65

This insures the operator's safety since it is thus impossible to open the disconnecting switch 11, 13 under load.

Assuming that the feeder disconnecting switch is in the circuit closing position, that is, that the contacts 11 and 13 are in engagement and that the circuit breaker 64 is closed and either the feeder 61 or the network 62 or both are energized, it will be impossible to turn the switch since the electromagnetic means 27 is energized and engages the interlocking sector 28. Under these conditions the switch parts are positioned as shown in Figs. 1, 2, 5 and 9. If for any reason it is desired to work on any of the equipment 70 in the vault or chamber containing the transformer 63 the circuit breaker 62 and the disconnecting switch, the operator must first arrange to have the feeder circuit 61 opened, for example, at the power station and must 75 effect the opening of the circuit breaker 64. The electromagnetic means 27 is thus de-energized and the locking sector 28 released. Whoever is authorized may unlock the padlock 53 thus unlocking the operating mechanism 40. Even though this mechanism were 80 not unlocked prior to the opening of the circuit breaker 64 and the feeder circuit 61, it would still be impossible to move the operating handle since the interlocking means 26, 27 and 28 would be engaged. Assuming, 85 however, that this interlocking means is released, then the operating handle 44 can be moved into the circuit open position shown in Fig. 6 after counter-clockwise movement 90 of the locking element 48 which moves the lug 49 out of the path of movement of the lug 51 as will be obvious from Fig. 5, and releases the pressure on the packing 55. The operating handle 44 may then be moved into 95 the position shown in Fig. 6, and, if desired, locked in this position by turning the locking element 48 clockwise into the position shown 100 in Figs. 6 and 8 with the locking lug 49 in the slot 50 on the operating handle 44. In this 105 position the padlock 53 may again be inserted in the registering eyes 52 if it is desired to lock the switch against unauthorized use.

If the switch is moved to the open position 110 shown in Figs. 3, 6 and 8, and left in this position with the locking element 48 in the locking position with pressure on the packing 55, it may be that an operator or maintenance man might come along and release 115 the member 48 and try to move the operating handle to the ground position. This, of course, cannot be done if the electromagnetic interlock 27 is energized. If, however, the switch is in the open position and the circuit breaker 64 is open and in the meantime the 120 feeder 61 has been energized for example by closing the switch at the power station, then the interlocking means 27 would be deenergized and if the operating member 44 could 125 be moved to the ground position a polyphase 130

short circuit would be put on the live feeder 61. This, of course, must not be done. If under these conditions the operator attempts to move the contacts 13 to the ground position he will find it impossible to do so since the pin 59 in the link 57 comes to the closed end of the slot 60 when the operating member 44 is in the switch open position. Consequently, the operating handle must be moved from the open position back to the closed position shown in Fig. 5 before the pin 59 can be released from the slot 60. However, when the operator makes this closing movement of the operating member 44 if the feeder 61 is energized the electromagnetic interlock 27 will be excited even though the circuit breaker 64 is open. Consequently, as soon as the switch is returned to the closed position it will be locked there by the electromagnetic interlock and the operator will be unable to move it from this position. If, however, the feeder 61 were not energized and the circuit breaker 64 were open when this return movement to the closing position is made, the operating handle would be free for movement to the ground position upon moving the link 57 so that its pin 59 moves outward in the slot 50 and away from the slot 60. The operating handle may then be moved substantially 180° to the position shown in Fig. 7. This is the grounding position of the switch with the contacts 12 and 13 in engagement, as shown in Fig. 4. In this position of the switch the return of the locking element 48 to the position shown in Fig. 7 restores the pressure about the shaft extension 45 and puts the lug 49 in the path of movement of the lug 51 on the operating member 44, and if desired, the switch may be locked in this position by inserting the padlock in the eyes 52. Upon the release of the locking lever 48, the switch can be returned from the ground position to the open position, but cannot be locked in this position since the link 57 will be in the path of movement of the lug 49. This will be apparent from Fig. 8, for the pin 59 will be in the lug 65 in line with the lug 49. In order to lock the switch in the open position the operating member 44 must be returned to the closed position, as shown in Fig. 5, where the pin 59 will automatically engage the slot 60. This automatic return is due to gravity when the operating mechanism is mounted as shown in Fig. 1, but it will be apparent that any other suitable biasing means could be employed.

While I have shown and described my invention in considerable detail, I do not desire to be limited to the exact arrangements shown but seek to cover in the appended claims all those modifications that fall within the true spirit and scope of my invention.

What I claim as new and desire to secure by Letters Patent of the United States is

1. An electric switch including relatively movable contact means and actuating means therefor including an operating member movable to a plurality of positions and means for permitting a limited movement of said member from one of said positions including a locking element mounted on said member for movement relatively thereto, said element being releasable only when the member is in said one of said positions to permit a greater movement of the member. 70

2. An electric switch including relatively movable contact means and actuating means therefor including an operating member movable to a plurality of positions and means for permitting a limited movement of said member from one of said positions including relatively movable interlocking elements releasable only when the member is in said one of said positions to permit a greater movement of the member. 75

3. An electric switch including two relatively stationary spaced contacts, a cooperating movable contact, and actuating means therefor including a rotatable operating member, an insulating support for said movable contact pivotally mounted on said operating member and relatively movable guiding elements for controlling the angular position of said support on rotation of said operating member to actuate the movable contact from a position adjacent one of the stationary contacts to a position adjacent the other stationary contact, one of said elements being secured to said support. 80

4. An electric switch including relatively movable cooperating contacts and actuating means therefor including a rotatably mounted operating member, an insulating member for supporting one of said contacts pivotally mounted on said operating member and relatively movable means for controlling the angular position of the insulating member. 85

5. In an electric switch having relatively movable contacts mounted in a chamber, switch operating means including a member extending into the chamber, and means for maintaining a substantially fluid tight seal about said member arranged to be actuated to sealing position when the member is in a predetermined position and when in the sealing position to prevent the movement of the member. 90

6. An electric switch including relatively movable contacts and actuating means therefor including an operating member movable to a plurality of positions, means for permitting a limited movement of said member from one of said positions releasable when the member is in said one of said positions to permit a greater movement of the member and means adapted to be operated when the member is in any one of said positions to lock the member against movement. 95

7. An electric switch including two rela-

tively stationary contact means and a movable contact means arranged to be positioned to engage either of said stationary contact means, means for actuating the movable contact means including an operating member arranged on movement in one direction to disengage the movable contact means from one of the stationary contact means, means for limiting the movement of the operating member in said direction whereby to prevent engagement of the movable contact means with the other stationary contact means, releasable to permit said engagement only when the movable contact means is in engagement with said one of said contact means.

8. An electric switch including two relatively stationary spaced contact means, a cooperating movable contact means, and actuating means therefor including a shaft mounted between said stationary contact means, a crank on said shaft, an insulating support for said movable contact means pivotally mounted on said crank whereby on a predetermined rotation of said shaft the movable contact means is moved from a position adjacent one stationary contact means to a position adjacent the other stationary contact means, and means for controlling the angular position of said support including an arm extending from the support and a guide for the arm.

9. An electric switch including two relatively stationary spaced contact means, a cooperating movable contact means, and means for actuating said movable contact means to engage either of said stationary contact means including a member for supporting the movable contact means arranged for movement in an arcuate path, and means for controlling the angular position of said member during its movement in said path.

10. An electric switch having relatively movable contacts mounted in a chamber containing an insulating fluid, switch operating means including a member extending into the fluid containing chamber and movable to a plurality of positions, means for permitting a limited movement of said member from one of said positions releasable when the member is in said positions to permit a greater movement of the member, and means for maintaining a substantially fluid tight seal about said member arranged to be actuated to sealing position when the member is in one of said positions and when in the sealing position to prevent movement of the member.

11. An electric switch including relatively movable contact means and actuating means therefor including an operating member movable to a plurality of positions and means for permitting a limited movement of said member from one of said positions including relatively movable elements respectively provided with a slot and a projection mounted

for movement in the slot, said projection being removable from said slot only when the operating member is in a predetermined position to permit a greater movement of the member.

12. An electric switch including relatively movable contact means and actuating means therefor including an operating member movable to a plurality of positions and means for permitting a limited movement of said member from one of said positions including a stationary element provided with a slot and a locking element pivotally mounted on said member and having a portion movable in said slot and removable therefrom only when the member is in said one of said positions to permit a greater movement of the member.

In witness whereof I have hereunto set my hand this 10th day of June, 1929.

HAROLD N. BEEBE. 85

CERTIFICATE OF CORRECTION.

Patent No. 1,803,163.

Granted April 28, 1931, to

HAROLD N. BEEBE.

It is hereby certified that error appears in the printed specification of the above numbered patent requiring correction as follows: Page 5, line 51, claim 10, before "positions" insert the words one of said; and that the said Letters Patent should be read with this correction therein that the same may conform to the record of the case in the Patent Office.

Signed and sealed this 2nd day of June, A. D. 1931.

(Seal)

M. J. Moore,
Acting Commissioner of Patents.
